(57) **CLAIM**

I claim the ornamental design for a vanity mirror, as shown and described.

DESCRIPTION

FIG. 1 is a front, perspective view of the vanity mirror of the present invention.

FIG. 2 is a rear, perspective view of the vanity mirror of FIG. 1.

FIG. 3 is a front elevation view of the vanity mirror of FIG. 1.

FIG. 4 is a rear elevation view of the vanity mirror of FIG. 1.

FIG. 5 is a side elevation view of the right side of the vanity mirror of FIG. 1.

FIG. 6 is a side elevation view of the left side of the vanity mirror of FIG. 1.

FIG. 7 is a top plan view of the vanity mirror of FIG. 1; and, FIG. 8 is a bottom plan view of the vanity mirror of FIG. 1. In the drawings, the broken lines depict portions of the vanity mirror that form no part of the claimed design.
